ORDNANCE

John C. Trotter, Williamsville, N. Y., assignor to
Bell Aircraft Corporation, Buffalo, N. Y.

Application October 16, 1942, Serial No. 462,255

5 Claims. (Cl. 89—37.5)

This invention relates to ordnance, more particularly to remote controlled gun sighting means.

One of the objects of the present invention is to provide an improved remote controlled gun sighting mechanism for use in conjunction with high altitude aircraft wherein the gun sight mechanism is disposed within a pressurized aircraft cabin or enclosure while the gun mechanism is mounted exteriorly thereof. Another object of the present invention is to provide a sighting mechanism of the character described which is of improved accuracy characteristics. Other objects and advantages of the invention will appear from the specification hereinafter.

In the drawing:

Fig. 1 is a fragmentary sectional view of an airplane mounting a gun and gun sighting arrangement of the invention;

Fig. 2 is an elevation, on an enlarged scale, of a portion of the gun and gun sight synchronizing mechanism; and,

Fig. 3 is a section taken along line III—III of Fig. 2.

The drawing illustrates the invention in conjunction with a platform such as a combat airplane including a fuselage or gunner's nacelle as indicated at 10 from which extends a gun enclosure indicated generally at 12. Thus, it will be understood that the enclosures 10—12 may be disposed either at the nose or tail of an aircraft, or at any side or top or bottom portion thereof. A gun 14 of the aerial cannon or machine gun type is shown mounted within the enclosure 12 by means of a yoke and pivot mount indicated generally at 16; and it will be understood that the gun will be supported by the yoke 16 upon a base 18 in such manner that the gun is freely pivotable both vertically and horizontally for elevational and azimuthal aiming adjustments thereof. The enclosure structure 12 will of course necessarily be suitably apertured to accommodate aiming swinging movements of the gun barrel, and it will be understood that therefore the interior of the gun enclosure 12 will be at external atmospheric pressures.

For high altitude service the gunner's nacelle 10 will preferably be artificially pressurized by means of any suitable air compression mechanism, which forms no part of the present invention; but it will be understood that to enable the compressor mechanism to effectively pressurize the nacelle 10 a pressure-proof partition or wall as indicated at 20 must be disposed to seal the nacelle 10 from the gun enclosure 12.

Thus, the gunner will be accommodated within an artificially pressurized enclosure, and the wall portions thereof will be provided with suitable window sections, as at 21, for observation purposes, as is well understood in the art.

The gun sighting mechanism may comprise, as illustrated at 22 (Fig. 1), any suitable type of telescope sight or the like; and the sight device will be pivotally mounted as indicated at 24 upon a yoke 26 which in turn is received in rotatable relation by a vertically socketed base member 28, whereby the sight telescope is freely pivotable both in elevation and azimuth for target sighting purposes. A gear quadrant 30 is carried by the sight 22 to be concentric of the pivot axis at the connection 24, and a worm gear 32 is mounted to mesh with the quadrant 30 and to be driven by an electric motor 34 which is fixed to stationary aircraft structure by means of a bracket 36.

The motor 34 is arranged to be energized by means of a battery as indicated at 36, or in the alternative through means of connection to any other suitable power supply; and conductors 37—38 are connected to comprise a control circuit for the motor 34 arranged to be actuated through a rheostat as indicated at 40. The rheostat control lever 42 is arranged to extend therefrom for convenient manipulation by the gunner for suitable reverse direction control of the motor operation, whereby the telescope sight 22 will be driven by the motor 34 to elevationally adjusted positions for aiming at a target. Thus, the rheostat lever 40 will be adapted to be swung upwardly by the gunner from its central position to close the circuit controlling operation of the motor 34 in such direction as to deflect the sight 22 downwardly, while downward movement of the rheostat lever 40 will cause the motor to operate in reverse direction to elevate the muzzle of the telescope.

The rheostat grid base is adjustably mounted upon the aircraft and linked to the telescope sight 22 by means of a strut 46, whereby as the sight shifts in response to operation of the motor 34 to a position corresponding to the control movement of the rheostat lever, the rheostat device will automatically return to open-circuit condition. Hence, in response to each aiming adjustment movement of the lever 40 the motor will drive the telescope sight to a corresponding adjusted position, whereupon the link 46 will automatically return the control to motor de-energized condition pending further manipulation of the control lever.

A flexible torque shaft or cable, such as indicated at 50, or any other suitable motion transmission device is connected at one end to the armature of the motor 34 and at its other end to the drive shaft 52 of a gear 54 carried within a differential casing 55. The opposite differential gear 56 is similarly mounted upon the casing 55 and is keyed to a shaft 58 engaging in driving relation with a torque cable 60 leading into connection with the driven shaft of a hydraulic motor 62. The shaft of the motor 62 also connects in driving relation with a worm 64 geared to a toothed quadrant 66 which is carried by the gun 14 concentrically of the elevational adjustment axis thereof. The hydraulic motor 62 is arranged to be driven by circulation of pressurized fluid therethrough by means of conduits 68-69 leading from the motor 62 to a pump 70.

The pump 70 is of the variable displacement type of which several suitable models are presently available, and per se forms no part of the present invention. The displacement control lever of the pump 70 is indicated at 72 and is connected by means of a link 74 and suitable pivot connections to an arm 77 extending through a slotted portion of the differential casing 55. The arm 77 clamps at its inner end upon a shaft 78 which is mounted upon the inner race of an annular ball bearing 80 carried within the casing 55. The shaft 78 extends inwardly from the bearing 80 in a direction radially thereof and toward the axis of rotation of the differential gears 54-56; and the bearing 80 is arranged concentrically of such axis. The floating gear 82 of the differential mechanism is rotatably mounted upon the shaft 78, and is carried thereby so as to mesh with the gears 54-56. Thus, it will be understood that in response to any differential movements of the gears 54-56 the floating gear 82 will be given a corresponding planetary motion whereby the shaft 78 will be moved laterally within the casing 55 and will thereby carry the arm 77 to actuate the control crank 72 of the pump 70.

As stated, the pump 70 will be preferably of the type that is constantly operating, and will deliver fluid through the conduits 68-69 at rates varying from zero to maximum pump capacity as controlled by the arm 72. Hence, the fluid pressures acting upon the motion producing elements of the motor 62 will be constant and of maximum order, and the motor 62 will therefore always be under firm control by the hydraulic system and the possibility of lost motion or operational lag is avoided.

Thus, it will be understood that whenever the rheostat control lever 42 is adjusted to a new position, the motor 34 will be thereby energized to drive the gun sight toward a corresponding position of elevational adjustment, while the torque cable 50 simultaneously actuates the differential gear 54 to displace the floating gear 82 in such manner as to cause the control arm 72 of the pump 70 to be actuated away from its neutral or non-delivery position. The parts of the mechanism are so arranged that the response of the pump 70 to the control operation just referred to will cause the delivery of a supply of pressurized fluid to the hydraulic motor 62 so as to cause the motor to drive the gun 14 to an elevationally adjusted position corresponding exactly to the adjusted position of the gun sight 22. The driving connection between the motor 62 and the differential gear 56 will thereupon function to return the differential system to its neutral condition, while the rheostat mechanism has

5 automatically returned itself to neutral condition as explained hereinabove. The mechanism is of course adapted to provide the aiming adjustment movements referred to in either direction of elevational adjustment.

10 It will be appreciated that a particular feature and advantage of the arrangement of the invention resides in the fact that the operative connections extending between the pressurized nacelle 10 and the open gun enclosure 12 consists only of one torque cable and two pressure-sealed fluid conduits, all of which may be arranged with utmost facility to extend through the partition wall 20 in atmospheric pressure-sealing relation. Thus, the arrangement of the invention avoids the great disadvantages and objections of prior art remote control gun sighting arrangements such as employ linkages or push-pull actuating mechanisms between the gun and the gun sight elements and which are particularly difficult to pressure-seal due to the nature of the control movements thereof.

20 To actuate the gun and gun sight units for azimuthal adjustments, motors similar to the motors 34-62 hereinabove referred to will be coupled to the gun sight and gun elements, respectively, for producing rotation thereof in horizontal directions. In such case the rheostat control handle 42 would be coupled to a second rheostat device disposed in a horizontal plane, whereby the control handle would be universally manipulatable to procure corresponding combination elevational and azimuthal adjustments of the gun sight and gun units. To this end the combination 25 system would also include duplicate differential and hydraulic pump mechanisms of the type illustrated and referred to hereinabove.

30 It is contemplated that in lieu of the electric motor 34, any other suitable type of motor device 40 may be employed for the purpose such as a hydraulic motor or the like; and that the control handle 42 would thereupon be connected through a suitable control device to provide the type of motor control referred to. It will also be understood that in lieu of the torque cable and hydraulic systems connecting with the differential mechanism of the drawing, any other suitable form of movement-synchronizing means may be employed such as variable mechanical transmissions or Selsyn transmissions, or the like; and that although only one form of the invention has been illustrated and described in detail, it will be understood that various changes may be made therein without departing from the spirit of the 45 invention or the scope of the appended claims.

50 I claim:
1. In combination, a gun mounted for pivotal movements upon a platform fluid pressure motor means mounted upon said platform and geared to said gun for pivoting the latter, gun-sight means mounted upon said platform to pivot relative thereto in directions corresponding to pivotal movements of said gun, motor means geared to said gun-sight for pivoting the latter, control 55 means for said gun-sight motor means adapted to be manually manipulated to procure motor-actuated pivoting movements of said gun-sight, first torque transmission means coupled to said gun-sight motor means, a second torque transmission means coupled to said gun for actuation in response to pivoting movements thereof, differential gear means separately coupled at opposite sides thereof to said first and said second mentioned torque transmission means and having a floating gear member responsive to differ-

ential movements of said torque transmission means, fluid pump means connected to said gun actuating motor means for operating the latter and having a displaceable control member, and means connecting said displaceable control member and said floating gear for actuation in response to planetary movements of said gear to control said pump.

2. In combination, a gun pivotally mounted upon a base, hydraulic motor means mounted upon said base and geared to said gun for pivoting the latter, gun-sight means disposed remotely from said gun and mounted to pivot in aiming directions corresponding to pivotal movements of said gun, motor means geared to said gun-sight for pivoting the latter, control means for said gun-sight motor means adapted to be manually manipulated to procure motor-actuated pivoting movements of said gun-sight, first torque transmission means coupled to said gun-sight and a second torque transmission means coupled to said gun for respective actuation in response to pivoting movements thereof, differential gear means separately coupled at opposite sides thereof to said first and said second mentioned torque transmission means and having a floating gear member responsive to differential movements of said torque transmission means, an arm extending from said floating gear member, hydraulic pump means connected to said gun actuating motor means for operating the latter and having a displaceable control member, and means connecting said displaceable control member and said floating gear arm for actuation in response to planetary movement of said gear to control said pump.

3. In combination, a gun mounted for pivotal movements upon a base, reversible hydraulic motor means mounted upon said base and geared to said gun for pivoting the latter, an atmosphere-sealed enclosure disposed remotely from said gun and adapted to accommodate a gunner therein, gun-sight means mounted within said enclosure to pivot relative thereto in directions corresponding to pivotal movements of said gun, reversible motor means geared to said gun-sight for pivoting the latter, control means for said gun-sight motor means adapted to be manually manipulated to procure motor-actuated pivoting movements of said gun-sight, first torque transmission means coupled to said gun-sight motor means, a second torque transmission means coupled to said gun for actuation in response to pivoting movements thereof, differential gear means separately coupled at opposite sides thereof to said first and said second mentioned torque transmission means and having a floating gear member responsive to differential movements of said torque transmission means, reversible direction pump means connected to said gun actuating motor means for operating the latter and having a direction control member, and means connecting said direction control member and said floating gear for actuation in response to planetary movements of said gear to control said pump.

4. In combination, a gun mounted for pivotal movements upon a platform, reversible direction fluid pressure type motor means mounted upon said platform and geared to said gun for pivoting the latter, gun-sight means mounted upon said platform to pivot relative thereto in sighting directions corresponding to pivotal movements of said gun, reversible motor means geared to said gun-sight for pivoting the latter, control means for said gun-sight motor means adapted to be manually manipulated to procure motor-actuated pivoting movements of said gun-sight, first torque transmission means coupled to said gun-sight and a second torque transmission means coupled to said gun for respective actuation in response to pivoting movements thereof, differential gear means separately coupled at opposite sides thereof to said first and said second mentioned torque transmission means and having a floating gear member responsive to differential movements of said torque transmission means, motor control means connected to said gun actuating motor means for controlling the latter and having a displaceable control member, and means connecting said floating gear and said displaceable control member for actuation of the latter in response to planetary movements of said gear.

5. For use as an ordnance accessory to high altitude aircraft, a gun battery comprising in combination, a base, a gun mounted for pivotal movements upon said base, hydraulic pressure motor means mounted upon said base and geared to said gun for pivoting the latter, an atmosphere-sealed walled enclosure mounted upon said aircraft and disposed remotely from said gun and adapted to accommodate a gunner therein, gun-sight means mounted within said enclosure to pivot relative thereto in directions corresponding to pivotal movements of said gun, motor means geared to said gun-sight for pivoting the latter, control means for said gun-sight motor means adapted to be manually manipulated to procure motor-actuated pivoting movements of said gun-sight, first torque transmission means coupled to said gun-sight motor means, a second torque transmission means coupled to said gun for actuation in response to pivoting movements thereof and extending into said enclosure through a pressure-sealed apertured wall portion thereof, paired differential gear means separately coupled to said first and said second mentioned torque transmission means and meshing with a floating gear member responsive to differential movements of said torque transmission means, hydraulic pump means mounted within said enclosure and connected to said gun actuating motor means through means of pressure-sealed conduit devices extending through a pressure-sealed aperture portion of said enclosure wall for operating the latter and having a displaceable control member, and means connecting said displaceable control member and said floating gear for actuation in response to planetary movement of said gear to control said pump.
